UNITED STATES PATENT OFFICE.

ANDREW M. SMITH, OF FALLS CREEK, PENNSYLVANIA.

MILK-RACK AND REFRIGERATOR.

SPECIFICATION forming part of Letters Patent No. 634,070, dated October 3, 1899.

Application filed February 4, 1899. Serial No. 704,567. (No model.)

To all whom it may concern:

Be it known that I, ANDREW M. SMITH, a citizen of the United States, residing at Falls Creek, in the county of Clearfield and State 5 of Pennsylvania, have invented a new and useful Milk-Rack and Refrigerator, of which the following is a specification.

This invention is in the nature of a device in which to carry bottled milk, the object of 10 the invention being to provide for the use of milkmen and others a convenient carrying-receptacle for bottled milk by means of which the milk may also be kept cool.

With this object in view my invention consists in a water-tight box or case adapted to 15 be carried in a wooden frame or crate and supplied with a wire-netting rack or false bottom, a bottle-rack thereon, and a central ice basket or chamber, the improved construction, arrangement, and combination of the 20 parts of which will be hereinafter fully described and afterward specifically pointed out in the claims.

In order to enable others skilled in the art 25 to which my invention most nearly appertains to make and use the same, I will now proceed to describe its construction and operation, having reference to the accompanying drawings, in which—

30 Figure 1 is a detail perspective view of the cover for the ice-cage. Fig. 2 is a similar view of the ice-cage. Fig. 3 is a similar view of the bottle-rack. Fig. 4 is a similar view of the false bottom or wire-netting. Fig. 5 is 35 a similar view of the water-tight box. Fig. 6 is a longitudinal vertical sectional view through the invention, the parts being assembled in their operative positions.

Like letters of reference indicate the same 40 parts throughout all the figures of the drawings.

Referring to the drawings by letters, A indicates a wooden crate or frame to serve as a receptacle and protector for a longitudinal 45 metallic box B, made water-tight and formed with holes B' near the top of its ends to facilitate handling, the wooden crate A being also provided with handles A', similarly situated.

50 C indicates a metallic frame of the proper size to fit within the water-tight box B. This

frame supports a wire-netting or other open-work D, in the center of which is secured a metallic frame E.

F indicates an inverted metallic pan or rack 55 provided with any suitable number of openings F' of the proper size to receive and hold upright the usual bottles, in which milk is carried. Flanges G are raised in the center of the rack F and are provided with notches G'. 60

H indicates a wire or other open-work cage or basket adapted to fit in the frame composed of the flanges G of the bottle-rack and the frame E of the false bottom D. This cage or basket is provided at its upper edge with 65 outwardly and downwardly projecting hooks H' to engage in the notches G' of the bottle-rack, whereby the cage is suspended with its bottom a short distance above the bottom of the box B when the parts are assembled. A 70 lid I is provided to fit over and close the top of the cage or basket H, notches I' being provided to fit over the hooks H'.

In use the box B is set in the wooden rack or frame A, the false bottom C D is placed in 75 the box B, resting upon the frame thereof, the bottle-rack F is next placed in position resting upon the network of the false bottom and prevented from moving about in the box by means of spring-fenders F' on its 80 outer sides, which fit with moderate pressure against the inside of the box B, and the cage H is inserted in the central openings in the bottle-rack F and the false bottom, being supported by the hooks H', engaging in the 85 notches G' of the flanges G. Filled bottles may now be stored in the openings F' in the bottle-rack F, ice deposited in the cage H, and the lid I placed in position to close the top of the cage, when the whole device will 90 be ready for practical use.

By the use of my invention milkmen and others may carry bottled milk from place to place, preserving the bottles against breakage and at the same time keeping the milk 95 cool and pure, and while I have illustrated and described the best means now known to me for carrying out my invention I do not wish to be understood as restricting myself to the exact details of construction shown and described, but hold that any slight changes or variations therefrom such as might sug-

gest themselves to the ordinary mechanic would be clearly comprehended within the limit and scope of my invention.

Having thus fully described my invention, 5 what I claim as new, and desire to secure by Letters Patent of the United States, is—

1. A milk-rack provided with a false bottom of network, an inverted pan-shaped bottle-rack having suitable openings in which 10 to stand the bottles while resting upon the false bottom, the false bottom and bottle-rack having central openings surrounded by vertical flanges, and an open-work ice-cage adapted to be seated in the central openings 15 referred to and provided with hooks for suspending it upon the flanges surrounding the

central opening of the bottle-rack, substantially as described.

2. The milk-rack and refrigerator herein described comprising the water-tight pan B, 20 the open-work false bottom C D provided with the frame E in the center thereof, the inverted pan-shaped bottle-rack F having openings F' and a central opening surrounded by flanges G having notches G', the open-work ice-cage H, having hooks H' for suspending it from the flanges G, and a cover therefor, substantially as described. 25

ANDREW M. SMITH.
